UNITED STATES PATENT OFFICE.

GEORGE WALKER, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A DISPLAY-STAND.

43,171.

Specification for Design.

Patented Oct. 15, 1912.

Application filed August 10, 1912. Serial No. 714,476. Term of patent 7 years.

To all whom it may concern:

Be it known that I, GEORGE WALKER, a citizen of the United States, and a resident of New Britain, in the county of Hartford, State of Connecticut, have invented a new, original, and ornamental Design for a Display-Stand, of which the following is a specification, reference being had to the accompanying drawing, forming part hereof.

The drawing gives a perspective view of the structure.

I claim:

The ornamental design for a display stand as shown.

GEORGE WALKER.
